UNITED STATES PATENT OFFICE.

JOSEPH P. CONNOR, OF TOWSON, MARYLAND, ASSIGNOR TO UNITED STATES ASPHALT REFINING COMPANY, OF NEW YORK, N. Y., A CORPORATION OF SOUTH DAKOTA.

CORRUGATING MACHINE.

Application filed November 2, 1922. Serial No. 598,595.

To all whom it may concern:

Be it known that I, JOSEPH P. CONNOR, a citizen of the United States, residing at Towson, in the county of Baltimore and State of Maryland, have invented new and useful Improvements in Corrugating Machines, of which the following is a specification.

This invention relates to corrugating or fluting machines, and particularly to a device for forming longitudinal corrugations in a metal sheet, which is especially adapted for use in the construction of expansion joints for roads, pavements, and the like.

One object of the present invention is to provide a machine of simple and efficient construction by which the continuous corrugating of sheets suitable for expansion joints in roadways and pavements may be produced rapidly and at small cost of production, the construction being such that the sheet will be delivered properly corrugated and with its longitudinal margins properly smooth and finished so that the strip will be in condition for handling.

A further object of the invention is to provide means whereby the strip may, if desired, be curved laterally so as to give a strip suitable for use with roadways and pavements having a crowned or curved surface.

Referring to the drawings, wherein is shown a preferred embodiment of my invention—

Figure 1 is a view showing the delivery end of the machine.

Fig. 2 is a side elevation view of the machine.

Fig. 3 is a top plan view.

Fig. 4 is a vertical sectional view of the device.

Fig. 5 is a top plan view showing a laterally deflected trough for receiving the corrugated sheet.

Fig. 6 is a view of a sheet after it has issued from the trough shown in Fig. 5.

Fig. 7 is a sectional view of the trough showing a corrugated sheet therein.

Referring to the drawings, like numbers indicating like parts in the various figures, 10 denotes a base plate to which is secured the side frames 11, said frames being maintained in fixed position by any suitable means such as the bolts 12, as shown.

The lower portions of the side frames 11 are each provided with stationary bearings 13 in which is journaled the shaft 14 which carries the lower corrugated roller 15. The upper portion of the said frame 11 is provided with elongated recesses 16 which act as guideways for the bearing blocks 17 that carry the shaft 18 on which is mounted the adjustable roll 19.

For effecting the proper adjustment of the roll 19 relative to the roll 15, set screws 20 are connected to the movable bearing 17 and extend an appreciable distance above the frame 11 through threaded openings formed therein. It will be seen that the adjustment of the rolls is so effected that the intensity or degree of corrugation imparted to the metal may be varied, as desired.

The shaft 14 projects at both ends a suitable distance beyond the side frames 11 and has secured adjacent one end thereof the drive gear 22, which is adapted to be connected to any suitable drive means (not shown), while at the opposite end of the shaft 14 there is carried a gear 23, which is in mesh with a corresponding gear 24 on the shaft 18. It will thus be seen that the rolls 15 and 19 are adapted to move simultaneously upon rotation of the drive gear 22, which is preferably secured to the same shaft as the roll 15.

The rear end of each of the side frames 11 is provided with elongated slots 25 to which are adjustably mounted a pair of guide rollers 26 and 27 by means of the clamping bars 28 and 29, that are secured to the inner and outer faces, respectively, of the side frame by the bolts 30.

The flat sheet of metal is carried from the table 31 to the corrugated rolls through a pair of L-shaped guide bars 32 which are adjustably attached to the front ends of the frames 11 by means of the slots 33 and screws 34, as shown. A similarly shaped pair of guide bars 35 are adjustably positioned at the rear of the side frames 11 by the bolts 36 to receive the corrugated sheet as it issues from the rolls and conduct it to any suitable point of delivery. These bars 32 and 35 not only act as guides for conducting the metal to and from the corrugated rolls, but also as supports to tie the side frames together.

The corrugated rolls 15 and 19 are pref-

erably provided with end flanges 37 and 38, which tend to smooth and straighten out the edges of the metal being corrugated, so as to eliminate the rough edges formed on the 5 sheets under the pressure exerted by the rolls as the metal passes through the machine.

The delivery trough 39 (Fig. 5) receives the sheet 40 as it issues from the roll, the 10 said trough being suitably supported from the guide bars 35, and this trough may be straight, as shown in dotted lines in Fig. 5, or it may be of curved formation, as shown in full lines, and of such length as may be desired.

15 Where the curved trough is used, the stock issuing from the machine will be curved or bent laterally by the trough so as to produce a sheet such as is shown in Fig. 6. The 20 corrugated sheet curved, as shown in Fig. 6, is designed for use with a crowned road or pavement, and any desired curvature may be given to it by changing the curvature of the trough.

It is to be understood that while the 25 present disclosure is a preferred embodiment of applicant's invention, minor changes in construction and operation of the device may be made without departing from the spirit of the invention and the scope of the appended 30 claims.

I claim:

1. A corrugating machine of the class described having in combination a pair of side frames, each of which is provided with a 35 stationary bearing and an adjustable bearing, shafts carrying fluted rolls journalled in each of said bearings, said rolls adapted to be brought into predetermined adjustment relative to each other, means connected to the end of one of said shafts for simultaneously rotating said rolls, elongated slots in the rear ends of said frames, guide rollers 40 adjustably mounted in said slots, adjustable guides attached to the rear of said frames, and means associated with said guides for bending laterally the stock as it issues from the rolls.

2. A corrugating machine of the class described having in combination a pair of side 50 frames each of which is provided with a stationary bearing and an adjustable bearing, a corrugated roll journalled in each of said bearings, one of said rolls having smooth end flanges adapted to overlie the adjacent roll when said rolls are brought into mesh with each other, means on the shaft of one of said rolls for simultaneously rotating the rolls, guide rollers adjustably attached between said frames adjacent the rear ends thereof, and a longitudinally curved trough associated with said guide rollers for bending laterally the stock as it issues from the rolls.

60 3. A corrugating machine of the class described, having in combination a pair of 65

side frames each of which is provided with a stationary bearing and an adjustable bearing, a corrugated roll journalled in each of said bearings, one of said rolls having smooth end flanges adapted to overlie the 70 adjacent roll when the rolls are brought into mesh with each other, means on the shaft of one of said rolls for simultaneously rotating the rolls, guide rollers adjustably mounted between said frames adjacent their 75 rear ends, angle guides adjustably mounted to the front end of said frames, and guides adjustably attached to the rear of the frames.

4. A corrugating machine of the class described having in combination a pair of side frames, each of which is provided with a stationary bearing and an adjustable bearing shafts carrying fluted rolls journalled in each of said bearings, said rolls adapted to be brought into predetermined adjustment relative to each other, means connected to the end of one of said shafts for simultaneously rotating said rolls, elongated slots in the rear ends of said frames, guide rollers 90 adjustably mounted in said slots, and a trough secured to said guide rollers having a laterally deflected forward end.

5. A corrugating machine of the class described having in combination a pair of side frames, each of which is provided with a stationary bearing and an adjustable bearing, fluted rolls journalled in said bearings adapted to be brought into predetermined mesh with each other, a pair of guide 100 rollers mounted between said frames, a delivery trough connected to the side frames adjacent said rollers, said trough having a laterally deflected open end.

6. A corrugating machine of the class described having in combination a pair of side frames each of which is provided with a stationary bearing and an adjustable bearing, a corrugated roll journalled in each of said bearings, one of said rolls having 105 end flanges adapted to overlap the adjacent roll when said rolls are brought into mesh with each other, means on the shaft of one of said rolls for simultaneously rotating the rolls, guide rollers adjustably attached between said frames adjacent the rear ends thereof, a delivery trough adjustably secured to the rear of the side frames, said trough having a laterally deflected forward 110 end for imparting a longitudinal curve to the stock as it issues from the corrugated rolls.

7. A corrugating machine of the class described, having in combination a pair of side frames each of which is provided with a stationary bearing and an adjustable bearing, a corrugated roll journalled in each of said bearings, one of said rolls having end flanges adapted to overlie the adjacent roll when the rolls are brought into mesh with 120

each other, means on the shaft of one of said rolls for simultaneously rotating the rolls, guide rollers adjustably mounted between said frames adjacent their rear ends, angle guides adjustably mounted to the front end of said frames, a delivery trough secured to the rear guides having a laterally offset portion for imparting a longitudinal curve to the sheet as it issues from the corrugated rolls. In testimony whereof I have hereunto set my hand.

JOSEPH P. CONNOR.
